UNITED STATES PATENT OFFICE.

GEORGE N. BERTRAND, OF STAFFORD SPRINGS, CONNECTICUT.

STOP-MOTION FOR LOOMS.

1,238,628.

Specification of Letters Patent. Patented Aug. 28, 1917.

Application filed October 12, 1914. Serial No. 866,321.

To all whom it may concern:

Be it known that I, GEORGE N. BERTRAND, a citizen of the United States, residing at Stafford Springs, in the county of Tolland 5 and State of Connecticut, have invented certain new and useful Improvements in Stop-Motions for Looms; and I do declare the following to be a full, clear, and exact description of the invention, such as will enable others skilled in the art to which it appertains to make and use the same.

This invention relates to improvements in looms.

The object of the invention is to provide 15 a simply constructed device adapted to automatically close an electric circuit and stop the loom, should breakage of one or more of the heddle frames or horizontal supports occur.

20 With the above and other objects in view, the invention consists of certain novel features of construction, combination and arrangement of parts as will be more fully described and claimed.

25 In the accompanying drawings:—

Figure 1 represents a perspective view of a loom equipped with this improvement, said view being taken from the rear;

30 Fig. 2 is a plan view of the attachment detached;

Fig. 3 is a side elevation thereof showing the device applied and its support in section;

Fig. 4 is a transverse section taken on the line 4—4 of Fig. 2; and

35 Fig. 5 is a longitudinal section thereof.

In Fig. 1 of the drawings, a portion of the loom is conventionally shown, said loom having the usual harness or heddle frames H, to the lower sides of which are attached 40 the lower harness connections. These connections are here shown as comprising a plurality of metal members 5, which extend horizontally of the loom, and are pivoted at one of their ends as at 5^b to a loom brace 45 and connected at their other ends at 5^c to members 5^a connected to the heddle frames H. It is to be understood, however, that these connections may be of other constructions. It is beneath these horizontal members 50 that my attachment, now to be described, is positioned.

My attachment, above referred to, comprises a substantially rectangular metallic frame 1 having a V-shaped extension or attaching member 2 at one end, the apex of said member 2 having a bearing 3 therein

disposed longitudinally to receive a bolt adjustably connecting the device to a right angular bracket 3^a. This bracket 3^a is composed of a pair of arms 8 and 9, the arm 8 being longitudinally slotted as shown at 8^a for a purpose to be described and having one of its ends bolted to the bearing 3. The other arm 9 has a longitudinally extending open slot 9^a at one end thereof to provide 60 for adjustable connection with the arm 8, and the other end thereof is offset laterally as shown at 10' and provided with a transversely extending recess or notch 11, the purpose of which will be hereinafter 65 described.

A steel bar or rod 4 is shown mounted in the end members 1^a and 1^b of the frame 1 and is insulated therefrom by suitable insulating material 1^c. This bar or rod 4 as 70 shown in Figs. 1, 3, 4 and 5 is mounted in a plane above the plane of the end and side members of the frame.

A comb 6 is mounted in the frame 1 parallel with the rod 4, the ends thereof being 80 supported by the end members 1^a and 1^b of the frame and the teeth of said comb project laterally at right angles as shown.

In use, the attachment is disposed beneath the horizontal members 5 of the harness connections, by being attached to one of the loom braces B'. The notch or recess 11 in the arm 9 of the bracket is designed to engage the upper flange 7 of the loom brace as shown in Fig. 3 to assist in retaining the 85 device in operative position on said brace. The bracket 3^a being adjustable both horizontally and vertically, and having its horizontal arm 8 adjustably connected to the apex of the V-shaped extension 2, provides 90 an effective means for properly adjusting the frame 1 with respect to the horizontal members 5.

Current conducting wires 7 connect the bar or rod 4 with any suitable source of 100 electricity, such as a dry battery B and with an electromagnet E attached to the handle of the loom, such as is shown at 11 in U. S. Patent No. 936,847, dated October 12, 1909, whereby when the circuit is closed, said handle will be immediately thrown out of operative 105 position and the loom stopped.

The closing of the circuit is accomplished and the loom stopped by the breakage of the supporting means of the heddle frame H, 110 said breakage causing the corresponding member 5 to which the heddle frame is con-

nected to drop into contact with the bar 4, thereby closing the circuit and through the connection of the electromagnet E with the frame F of the loom, operating to stop the loom in a manner above described.

While the device is very simple in construction, it is very efficient in operation and may be attached to any loom, it being so positioned that when the harness strap or hook 10 which supports the harness breaks, the members 5 which are disposed above the rod 4 and guided in the teeth of the comb 6, will come in contact with the bar 4 and close the circuit, thus immediately throwing the loom out of operation and preventing all danger of defective work which would occur should the loom continue to operate.

I claim:

1. An attachment for looms comprising 20 an open frame, a comb extending across said frame, the teeth of said comb projecting laterally with respect to the plane of said frame, a metal bar extending across said frame and being insulatively fixed thereto, 25 and having means at one end thereof for connection to an electrical conductor, and an adjustable bracket adjustably connected to said frame and being provided with attaching means.
2. An attachment for looms comprising 30 an open rectangular frame, a comb extending longitudinally of said frame and attached at its end thereto, the teeth of said comb projecting at right angles to the plane of said frame, a metal bar extending longitudinally 35

of said frame and being insulatively fixed at its ends to the ends thereof, said bar having means at one end thereof for connection to an electrical conductor, a V-shaped extension at one end of said frame, the apex of 40 said extension projecting outwardly, and a right angular bracket adjustably connected at one end to the apex of said extension and having attaching means at the other end thereof, said bracket being adjustable horizontally and vertically.

3. The combination with a loom having metal members extending horizontally across the same and connected to the heddle frames thereof, of a frame attached to said loom and being disposed horizontally below said members, a comb extending across the last mentioned frame and having its teeth projecting upwardly and receiving said members therebetween, a metal bar extending across the last mentioned frame and insulated therefrom and being disposed slightly below the plane of said members to be engaged by the latter should the supports of the heddle frames to which they are connected break, and an electric circuit including said bar and said members having a magnet therein adapted to stop said loom when energized.

In testimony whereof I have hereunto set my hand in presence of two subscribing witnesses.

GEORGE N. BERTRAND.
